United States Patent Office

Des. 179,485
Patented Jan. 1, 1957

179,485

PLAYING CARD HOLDER

Clayton A. Laughlin, Minneapolis, Minn., assignor of one-half to Donald E. Harley and one-half to Cecil B. Woofter, both of St. Paul, Minn.

Application December 12, 1955, Serial No. 39,290

Term of patent 14 years

(Cl. D34—13)

The figure shows a perspective view of a playing card holder incorporating my design.

I claim:

The ornamental design for a playing card holder, as shown.
